ATTORNEY

UNITED STATES PATENT OFFICE

166,047

CABINET FOR TELEVISION RECEIVING SET

Joseph D. Portanova, Los Angeles, Calif., assignor
to Hoffman Radio Corporation, Los Angeles,
Calif., a corporation of California

Application April 18, 1950, Serial No. 9,305

Term of patent 3½ years

(Cl. D56—4)

To all whom it may concern:

Be it known that I, Joseph D. Portanova, a citizen of the United States, residing at Los Angeles, State of California, have invented a new, original, and ornamental Design for Cabinet for Television Receiving Set, of which the following is a specification, reference being had to the accompanying drawing, forming a part hereof, in which drawing:

Figure 1 is a perspective view of the side, top and front panels of a television receiving set showing my new design, and

Figure 2 is a side elevation view thereof, on a reduced scale.

The opposite side of the cabinet as shown in Figure 1 is the same as the side shown, and the rear is plain.

The characteristic features of my design for cabinet for television receiving set reside in the screen frame on the front having the configuration shown.

I claim:

The ornamental design for a cabinet for television receiving set, as shown and described.

JOSEPH D. PORTANOVA.
